UNITED STATES PATENT OFFICE.

JOHN FLAMMANG, OF ST. LOUIS, MISSOURI, ASSIGNOR TO OTTMAR G. STARK, OF ST. LOUIS, MISSOURI.

PROCESS OF MAKING PISTONS.

1,347,449.

Specification of Letters Patent. Patented July 20, 1920.

Application filed February 27, 1918. Serial No. 219,363.

To all whom it may concern:

Be it known that I, JOHN FLAMMANG, a citizen of the United States, residing at the city of St. Louis and State of Missouri, have 5 invented a new and useful Process of Making Pistons, of which the following is a specification.

This invention relates to the art of manufacturing pistons.

10 An object of the invention is to improve the art of manufacturing pistons whereby pistons may be produced that will function properly and with a high degree of efficiency without the use of piston rings or packing.

15 A specific object of the invention is to provide a method or mode of procedure of manufacturing pistons which will function properly and with a high degree of efficiency without the use of piston rings or any kind 20 of packing and which, because of qualities inherent in the construction of the piston, will coöperate so effectively with the cylinder that the passage of gas, steam or the like between the piston and the cylinder is prevented.

25 Various other objects and advantages will appear from the following description in which reference is made to the accompanying drawings illustrating a piston in several 30 stages of its construction in accordance with the present invention, and in which—

Figure 1 is a view partly in section illustrating a form of casting which may be used in the construction of the piston body.

35 Fig. 1^a is a plan view of the casting.

Fig. 2 is a view illustrating the casting after several stages or steps of treatment.

Fig. 3 is a view of the casting after the metal has been placed under tension so that 40 when the piston is finished and placed in the cylinder the piston will impart pressure against the cylinder wall all around.

Fig. 4 is an elevation of the casting while the metal above the wrist pin is held under 45 tension ready for the casting to be finished as to its circumferential surface.

Fig. 5 is a view illustrating the casting held under tension within a cylinder, in which the treatment of the body of the piston is finished and made ready for the head 50 plate to be applied thereto.

Fig. 6 is an elevation of a finished piston made in accordance with my invention.

Fig. 7 is a sectional view of the piston 55 mounted within a cylinder.

The body of the piston is made from a casting which is treated so that the upper portion of the casting in its finished form is of a diameter larger than the diameter of the cylinder for which the piston is intended, 60 and which when placed in the cylinder is held under tension so that the piston body will impart pressure against the wall of the cylinder all around thus dispensing with the use of piston rings and packing. The treatment to which the piston is subjected may consist either in grinding the piston to the form desired, or in spreading the piston by the wrist pin as hereinafter explained. The 65 resiliency of the material of the body of the piston is utilized so that the piston can expand and contract in conformity with the requirements in order to maintain perfect coöperation with the wall of the cylinder and prevent the passage of gas or steam between the piston and the cylinder. The resiliency of the metal may be utilized by different methods and in describing my invention by making reference to the annexed 70 drawing, I do not of course confine myself 75 to the use or practice of the present invention in manufacturing pistons of the identical construction illustrated. The drawings are only for the purpose of illustrating one 80 form of piston which may satisfactorily be 85 constructed by use of my present process.

In the particular embodiment illustrated the body of the piston is manufactured from a casting which in its original form illustrated in Fig. 1, comprises a lower ring 1, an upper ring 2, a number of connections 3 integrally uniting the upper and lower rings, and bosses 4 in which the wrist pin of the finished piston is mounted. In its original condition the casting also includes two arms 5 extending inwardly from diametrically opposite sides of the upper ring in the plane of the bosses 4; and said arms, as shown, have upward extensions 6.

The next stages or steps in the construction of the piston by my present process consist in the formation of inwardly and downwardly inclined holes 7 through the connections 3 and the bosses 4 and cutting the upper ring in two places at diametrically opposite points, as shown at 8, in order to form an upper ring composed of separate segmental sections which are adapted to press against the wall of the cylinder for which the piston is intended by the resili- 100 105 110

ency of the metal of the piston. Also, preferably, though not essentially, the body of the casting is turned or ground so as to give it a slightly tapered shape, larger at its upper end as will be understood by reference to Fig. 2.

The connections 3 are next placed under tension by inserting a wrist pin 9 in the holes 7. The wrist pin fits closely within the holes and in order to insert the wrist pin it is necessary to bend or spread apart to a slight extent the connections 3 until the holes are in accurate alinement. The wrist pin will hold the material in that shape so that the connections 3 are at all times under tension.

Next the two separated parts of the ring 2 are forced toward each other in order to bend inwardly and place under tension the connections 3 above the wrist pin. This may be accomplished in any desired manner as, for instance, by passing a bolt 10 through the extensions 6 and turning the nut on the bolt until the segmental sections 25 of the ring 2 are drawn to the desired position and the proper tension is given the connections 3 above the wrist pin. While the casting is thus held under tension the periphery of the casting is ground or turned and finished. The upper ring is finished to the diameter of the cylinder for which it is intended, while the lower ring 1 is of slightly less diameter than the diameter of the cylinder. Thus, when the piston is 30 placed within the cylinder after being finished, pressure will be imparted against the cylinder wall all around by the segmental sections of the ring 2, due to the fact that when the ring was finished it was held under tension to the diameter of the cylinder, and when released from the compressing device the resiliency of the metal will cause the ring 2 to exert the required pressure against the wall of the cylinder.

45 After the periphery of the piston has been finished to give the upper ring a diameter the same as the diameter of the cylinder for which the piston is intended, while the material is held under tension as described, the piston is placed within a cylinder 11 (Fig. 5) of the same diameter as the diameter of the cylinder for which the piston is intended, thus holding the piston compressed under tension after the bolt 10 is removed.

55 The upper portion of the ring 2 is then cut away below the arms 5 and in the form of a piston shown an internal groove 12 is formed in the ring 2. Also, either before the piston is placed in the cylinder or after removal therefrom as desired, a number of circumferential grooves 13 are formed in the lower ring 1, which grooves are adapted to receive an oil or lubricant whereby the necessary lubricant is applied between the piston and the cylinder in which it operates.

The head or top plate 14 of the piston is seated upon the ring 2 and interlocked therewith by a flange 15 engaging within the groove 12, or, as preferred, by keys 16 seated in grooves in the open ends of the ring 2 and engaging in grooves in the top plate 14, so that said keys will be effective not only to hold the top plate in connection with the piston body but will also be effective to close the spaces between the open ends of the ring 2 and thus prevent passage of gas through said spaces.

The split upper ring of the piston may be spread or opened sufficiently to permit the top plate to be applied, permitting the flange 80 to pass inside the opened ring until said flange seats in the groove 12, as shown.

The upper edge of the ring 1 is beveled to provide a scraping edge 17 which during upward movement of the piston will scrape the oil from the cylinder wall; and the lower edge of the ring 2 is beveled to provide a scraping edge 18 which during downward movement of the piston will scrape the oil from the cylinder wall.

90 By reference to Figs. 6 and 7 it will be understood that the finished piston has a body composed of an open upper ring of slightly larger diameter than the diameter of the cylinder for which the piston is 95 intended, and that when the piston body is compressed within the cylinder the segmental sections of the upper ring will impart a pressure against the cylinder wall all around sufficient to prevent the passage 100 of gas or steam and that the spaces between the ends of the segmental sections of the upper ring are also closed against the passage of gas or steam by the keys 16.

105 It will be apparent that the order in which the stages of treatment are performed in the manufacture of the piston is unimportant, and that the order of such performance may be optionally varied.

I claim:

110 1. The process of making a piston which consists in dividing the upper portion of the piston body into segmental sections; drawing the segmental sections toward each other; and forming the exterior periphery 115 of the segmental sections in cylindrical form while the said sections are held drawn together.

120 2. The process of making a piston, which consists in forming a piston body of a lower ring, an upper ring and connections integrally uniting the upper and lower rings; splitting the upper ring into segmental sections; drawing the segmental sections of the upper ring toward each other to place the 125 material under tension; and finishing the piston to a size in which the upper ring while compressed under tension is of the same diameter as the diameter of the cylinder for which the piston is intended.

3. The process of making a piston which consists in forming a piston body of a lower ring, an upper ring, and connections integrally uniting the upper and lower rings; 5 splitting the upper ring into segmental sections; tensioning the upper ring; and finishing the piston.
4. The process of forming a piston which consists in forming a piston body of a lower 10 ring, an upper ring integrally connected with the lower ring; splitting the upper ring into segmental sections; holding the material under tension; finishing the piston while under tension to a size in which the 15 upper ring is of the same diameter as the diameter of the cylinder for which the piston is intended; and connecting a top plate to the piston body.
5. The process of forming a piston which 20 consists in forming a piston body of a lower ring and an upper ring, and integral connections uniting the upper and lower rings; forming holes inclining inwardly and down-
- wardly through said connections; inserting a wrist pin in said holes whereby said connections are placed under tension; tensioning the metal above the wrist pin; and finishing the piston. 25
6. The process of forming a piston which consists in forming a piston body of a lower 30 ring, an upper ring, and connections integrally uniting said rings; splitting the upper ring into segmental sections; spreading said connections apart to hold the material under tension; drawing the upper 35 ring sections toward each other to place the material under tension; and finishing the surface of the piston.
7. The process of making a piston which consists in dividing the upper portion of 40 the piston body into segmental sections; tensioning said sections, and finishing the exterior surfaces of said sections while they are under tension by forming the exterior 45 surfaces on the same radius of curvature.

JOHN FLAMMANG.
